UNITED STATES PATENT OFFICE.

WILLIAM HENRY CRANE, OF PHILADELPHIA, PENNSYLVANIA.

SAFETY POCKET-RAZOR.

1,192,503.

Specification of Letters Patent. Patented July 25, 1916.

Application filed April 27, 1916. Serial No. 93,880.

To all whom it may concern:

Be it known that I, WILLIAM H. CRANE, a citizen of the United States, residing at Philadelphia, in the county of Philadelphia 5 and State of Pennsylvania, have invented certain new and useful Improvements in Safety Pocket-Razors, of which the following is a specification.

This invention relates to safety razors and 10 has for its object primarily to provide such a razor with a handle into which it may be folded, with no part exposed, so that it may be safely and conveniently carried in a coat or pants pocket in the same manner as is the 15 ordinary pocket knife, and further to provide for the adjustment of the angle of the razor with relation to the handle while keeping the same, in extended position, in the same vertical plane with the handle, and 20 further, to provide two pivotal movements, the axis of one being at right angles to the axis of the other so that strain on one pivotal point will not affect the frictional grip of the other and so that in shaving there will 25 be only one pivotal point about which the blade may turn, such possible movement being in the same vertical plane with the handle.

In the accompanying drawings. Figure 30 1 represents a side elevation of a device embodying my invention, the razor being extended and the cover plate being closed, indicating in dotted lines the two extreme angular positions of the blade or razor proper. 35 Fig. 2 represents a bottom view, the cover plate being raised to receive the razor blade and the latter being folded nearly into the hollow handle; Fig. 3 represents a perspective view of the device when in folded position; Fig. 4 represents a sectional view on line 4—4 of Fig. 1; and Fig. 5 represents in detail perspective the back-plate, thin blade and guard-plate of the razor proper in superposed relation.

45 Referring now in detail to the drawings, the razor proper or cutter or blade is composed of three elements, the guard-plate A, the blade B and back-plate C, all constructed in usual manner, being of the thin flexible 50 blade type, and held together and adjusted in relation to each other by means of nut D, as usual in this type. To hold the nut D in position when being applied to the threaded stem of back-plate C and to prevent its loss 55 when removed therefrom, I have provided a forked spring tongue E which is riveted

to the guard-plate A and receives and holds frictionally in its forked end the nut D, preventing the accidental disengagement of said forked tongue and nut, the latter being 60 annularly grooved at this point to aid in this action.

The inner end of the guard-plate A is rounded to fit in a corresponding recess of a plate 1, both of said plates being provided 65 with registering perforations through which is passed an adjusting screw 2 engaging with the threads of the perforation in plate A, this perforation being internally screw-threaded for this purpose. A spring-washer 70 3 is interposed between the head of said screw 2 and the face of plate 1 in order that guard-plate A and the blade B and plate C carried thereby may be held yieldingly in any angular position of adjustment in the 75 same vertical plane with said plate 1 and the handle 4. The inner end of this plate 1 is sleeved on a pivot rod 3 which passes through the hollow handle 4 near the open end of said handle, the axis of said rod 3 80 being at right angles to the axis of screw 2.

The hollow handle 4, above mentioned, has one side and one end open so that the cutter, 85 razor or blade may be extended therethrough. Hinged to one side or edge of the side opening is the cover plate 5 to cover said opening and it is provided with an inwardly presented lug 6 which will partially close the open end when the device is in folded position and which will engage and firmly 90 hold the plate 1 against movement with relation to the handle 4 when the cutter is out in extended position. When closed the cover plate 5 will be flush with the edges of said side opening and will be held in such 95 position by the resiliency of the handle 4 as a whole. For convenience in opening it may be provided with a finger piece 7 as shown.

The operation is obvious. Also, it is obvious that a safety razor, such as shown and 100 preferred by applicant, or any other form of razor or other cutter may be used in combination with the hollow receiving handle.

Having thus described my invention, what I claim to be new and desire to secure by 105 Letters Patent is:

1. A hollow handle having an open side and a cover-plate hinged to said handle to cover said side opening, in combination with a plate pivotally mounted in said handle to 110 turn laterally in and out of said open side and a razor mounted on said plate, said

plate and razor lying wholly within the handle when in their folded position and the cover plate being held flush with the edges of said side opening by the resiliency of the handle as a whole.

2. A hollow handle having an open side and an open end, and a cover plate hinged to said handle to cover said side opening and having a depending lug to partially close said end opening; in combination with a plate pivotally mounted in said handle to turn laterally in and out of said open side and end, and a safety razor mounted on said plate to turn in the plane in which the axis

of the pivot of said plate lies, said plate and cutter lying wholly within the handle when in their folded position and the cover plate being held flush with the edges of said side opening by the resiliency of the handle as a whole.

20 In testimony whereof, I have signed my name to this specification in the presence of two subscribing witnesses.

WILLIAM HENRY CRANE.

Witnesses:

AUGUST WAGNER,
CLARA C. STRUMPEN.
